UNITED STATES PATENT OFFICE.

JOSEPH MARION KING, OF JACKSONVILLE, FLORIDA.

FLUID-TRACTOR.

1,153,798.

Specification of Letters Patent. Patented Sept. 14, 1915.

Application filed April 27, 1912. Serial No. 693,566.

To all whom it may concern:

Be it known that I, JOSEPH MARION KING, a citizen of the United States, residing at Jacksonville, in the county of Duval and State of Florida, have invented certain new, and useful Improvements in Fluid-Tractors, of which the following is a specification, reference being had therein to the accompanying drawing.

10 This device particularly is adapted to use with the exhaust-conduits of internal-combustion engines, but it also is applicable to the exhaust-conduits of other motors and to other conduits within which fluid flows under pressure.

15 It is an object of the invention to utilize the energy present in exhaust or other fluids to do the following: to produce a flow of liquid, and to induce flow of spent fluids from an engine in such manner that the efficiency of the engine is increased. With these results in view, the device is formed and arranged in such manner that exhaust or other fluids, as gases from an internal-20 combustion engine, entering it as a motive medium will be so affected or modified that partial vacuums will be created, whereby there is produced a flow of fluid distinct from the motive medium, as water of a 25 cooling-jacket, and whereby the source of the motive medium is relieved to a considerable extent of atmospheric and other back pressures and the tendency of the motive medium to flow from the source will be increased. Further, the changes taking place 30 in the motive medium will reduce materially the sound ordinarily caused by emission of exhaust fluids from engines.

35 When read in connection with the description herein, the details of construction and arrangement of parts will be apparent from the accompanying drawing, forming part hereof, wherein an embodiment of the invention susceptible of use with internal-combustion engines is disclosed, for purposes of illustration.

40 While a preferred form of the invention is shown herein, and described as when used with an engine, it is to be understood that it 45 merely is illustrative of the principles of the invention, that the parts can be variously organized and adapted for use with other conduits supplying fluids, within the limits prescribed by the claims hereinafter, 55 without departing from the nature and spirit of the invention, and that it is not the

intention to be limited necessarily to the precise delineation herein in interpretation of the claims.

Like reference-characters refer to corresponding parts in the views of the drawing, of which—

Figure 1 is an exterior view of the device; Fig. 2 is a longitudinal sectional view; Fig. 3 is a transverse sectional view, on the line 3—3, Fig. 2; Fig. 4 is a transverse sectional view, on the line 4—4, Fig. 2; and Fig. 5 is a transverse sectional view, on the line 5—5, Fig. 2.

Having more particular reference to the drawing, 6 designates an outer casing or shell, preferably circular in cross-section, and contracted at each end, as shown at 7 and 8. Within the casing and extending from one contracted portion to the other is 75 an inner casing 9, which, with the contracted portions of the outer casing, constitutes a continuous exhaust-conduit from end to end of the device. The annular space between the outer and inner casings, designated by 80 10, constitutes a cooling-jacket, which is supplied with liquid, such as water, from any suitable source and by any suitable means, through an inlet 11 in the outer casing.

Near the receiving end 7 of the device is a 85 transverse conduit 12 opening to the cooling-jacket at opposite places in the inner casing, and from this conduit there extends toward the exit end a conduit 13 centrally positioned with respect to the device. Se- 90 cured to conduit 13, and constituting a continuation thereof, is a member 14, preferably cylindrical, which at its free end has inwardly-projecting lugs 15 screw threaded at their free ends. These lugs are sup- 95 ports for a dispersing and valve-supporting member 16, which is held in place by engagement of its intermediate threaded portion 17 with the threaded ends of the lugs. The member 16 is tapered or generally cone 100 shaped at each end, and one end portion ex- 105 tends beyond the member 14 toward the exit end 8, and the other lies wholly within member 14 and has at its end a cylindrical portion 18. Situated within the passage leading from the transverse conduit 13, which passage is formed by members 13 and 14, and adjacent to member 13, is a seat 19, with which a valve 20 cooperates to close the 110 passage. A stem 21 of the valve projects into member 16 at its cylindrical end, whereby the valve is supported, and the valve is

retained resiliently on its seat by a coil-spring 22 interposed between the valve and member 16. The construction and arrangement are such that the valve opens under 5 fluid influence exerted in direction of the exit end of the device and closes under positively-exerted influence.

A threaded flange 23 extends from the end portion 8 of the casings, and thereon is 10 screwed a cap member 24, having an outlet portion 25 constituting a portion of the longitudinal passage throughout the device. At the exit end of the inner casing 9 there is a seat 26, with which an outwardly-opening 15 valve 27 coöperates to close the passage in the casing against atmospheric pressure, the valve being susceptible of opening under the influence of fluid pressure in the inner casing. The valve is supported by having a 20 stem 28 project into a frame 29 positioned in the cap member, and the valve is held resiliently on its seat by a coil-spring 30 interposed between the valve and frame.

It will be seen that the device is so formed 25 and arranged that there is a continuous longitudinal passage from end to end, and that the valve 27 is in direct line of longitudinal movement or impulse of fluids moving or having a tendency to move in, into, or out 30 of the passage.

In use the receiving end of the device is connected with a conduit leading from the exhaust port or ports of an engine, the discharge end is connected with an exhaust 35 disposal conduit, and the cooling-jacket is connected at the inlet 11 with a liquid-supply conduit. In actual practice, the device, when thus associated with an internal-combustion engine, has operated to produce a 40 satisfactory flow of liquid through the cooling-jacket and to increase materially the speed of the engine.

Following is an explanation of the actions of and within the device, which is given as 45 illustrative of the principles of the invention: The exhaust or pressure fluids from an engine pass through the inner casing 9, entering the device under initial pressure, and they pass out at the discharge end, the valve 50 27 opening due to the inertia of the moving mass of fluids. The check-valve 20 prevents the exhaust fluids on initial impulses into the device from passing into the cooling-jacket or reacting against the liquid in the 55 jacket. The principle of operation here is the utilization of the momentary pressure lapses caused by the intermittent expulsion of the exhaust fluids and reduction of volume of gases remaining in the passage. After 60 an exhaust, or a portion thereof, is impulsively discharged from the device, there is a rebound or tendency of the atmosphere to flow into the device. Back flow of air is prevented by the valve 27 closing against atmospheric pressure, and the engine thereby

is relieved of the necessity of initially overcoming atmospheric pressure on the next exhaust impulse. When exhaust fluids pass through the device, they usually are of two or more atmospheric pressures, and they force out, when the engine is started, whatever air there is in the device and the exhaust-conduits. When the exhaust-fluids enter the inner casing, there are an immediate subsidence in volume resulting from 70 the lowering of temperature due to contact with cooler parts and a tendency of the atmosphere to flow in to fill the partial vacuum caused by such subsidence. Back flow of air is prevented by closing of valve 27 on 75 account of the rebound effect mentioned or by both that and the subsidence. It is found in practice that atmospheric pressure closes valve 27 prior to completion of a cycle of 80 exhaust. The partial vacuum, therefore, is 85 effective to induce flow from the exhaust source and thereby not only initially to relieve the engine of the effect of atmospheric pressure, but also to produce a "pull" of 90 fluids therefrom; and it also is effective on 95 fluids within the cooling-jacket. That is, there is a tendency of fluids to flow not only from the exhaust source, but also from the cooling-jacket, and under this tendency the valve 20 opens and a flow of liquid induced 100 from the jacket. In this manner water may be drawn from the cooling-jacket of the engine, or from any other desired source, as from the bilge of a boat, for example, and discharged outwardly of the device with the 105 exhaust fluids.

About three-sevenths of the product of combustion of a mixture of air and gasoline or similar fuels used in the operation of internal-combustion engines is water in an attenuated or gaseous form. As water from the cooling-jacket flows out of member 14, it is diffused or dispersed by the tapered projecting end of member 16, and thus the 110 impulses of exhaust fluids pass through a water-bath in their travel through the inner casing. That part of the exhaust fluids that is attenuated water or steam thereby is liquefied, and there results a subsidence in volume in addition to that incident to reduction of 115 temperature resulting from contact with cooled parts. Thus it will be seen that the exhaust and cooling fluids are subjected to a "pull" in addition to that occurring on initial movement of an exhaust impulse into the device. It is estimated that the reduction of 120 exhaust volume resulting from the water-bath is about three-sevenths. The remaining gases, principally nitrogen, also are reduced in volume in consequent of liberation of heat 125 on contact with water. Probably there is a difference of 100 degrees centigrade in the exhaust fluids between the engine exhaust-ports and the discharge end of the device, and that difference alone would cause a re- 130

duction in volume of about one-third the total volume of the exhaust, for it is estimated that 273 degrees centigrade of heat causes a gas to double in volume. Thus it 5 will be seen how the device is effective to produce the results stated.

Having thus described my invention, what I claim as new, and desire to secure by Letters Patent, is—

10 1. A device of the kind described having a mixing-chamber, in line of discharge through said chamber a valve permitting exit of fluids therefrom and closing in response to atmospheric pressure, a liquid-supply passage communicating with said mixing-chamber, and a valve positioned in line of flow from said passage and arranged to admit liquid therefrom to said mixing-chamber and to close in response to fluid pressure 20 in the opposite direction.

2. A device of the kind described having therein an exhaust-passage, a valve susceptible of opening under the influence of fluid pressure within the passage and of closing under the influence of atmospheric pressure, a liquid-supply conduit leading into said passage, a valve arranged to permit flow of liquid from said conduit into said passage and to prevent flow of fluids in the opposite 25 direction in said conduit, and means whereby liquid from said conduit is diffused in said passage in the path of exhaust fluids therein.

3. A device of the kind described having therein an exhaust-passage, a valve susceptible of opening under the influence of fluid pressure within the passage and of closing under the influence of atmospheric pressure, a liquid-supply conduit leading into said 30 passage, a valve arranged to permit flow of liquid from said conduit and to prevent flow of fluids in the opposite direction in said conduit, and a member having a tapered end in the path of flow of liquid from said conduit whereby liquid is diffused in said passage in the path of exhaust fluids therein.

4. A device of the kind described having therein an exhaust-passage, a valve susceptible of opening under the influence of fluid pressure within said passage and of closing under the influence of atmospheric pressure, a liquid-supply conduit and a conduit member communicating therewith and projecting longitudinally into said exhaust-passage, 50 means whereby liquid from said conduit member is diffused in said passage in the path of exhaust fluids therein, and a valve arranged to permit flow of liquid from said conduits into said passage and to prevent flow of fluids in the opposite direction in said conduits.

5. A device of the kind described having therein an exhaust-passage, a liquid-supply conduit and a conduit member communicat- 65 ing therewith and projecting longitudinally

into said exhaust-passage, means whereby liquid from said conduit member is diffused in said passage in the path of exhaust fluids therein, and a valve arranged to permit flow of liquid from said conduits into said passage and to prevent flow of fluids in the opposite direction in said conduits. 70

6. A device of the kind described having therein an exhaust-passage, a liquid-supply conduit and a conduit member communicating therewith and projecting longitudinally into said exhaust-passage, a member supported by said conduit member and having a tapered end in the path of flow of liquid therefrom whereby liquid is diffused in said 75 exhaust-passage in the path of exhaust fluids therein, and a valve arranged to permit flow of liquid from said conduits into said exhaust-passage and to prevent flow of fluids in the opposite direction in said conduits. 80

7. A device of the kind described having therein an exhaust-passage, a valve susceptible of opening under the influence of fluid pressure within said passage and of closing under the influence of atmospheric pressure, a liquid-supply conduit and a conduit member communicating therewith and projecting longitudinally into said exhaust-passage, a member supported by said conduit member and having a tapered end projecting longitudinally therefrom whereby liquid is diffused in said passage in the path of exhaust fluids therein, and a valve arranged to 90 permit flow of liquid from said conduits into said passage and to prevent flow of fluids in the opposite direction in said conduits. 95

8. A device of the kind described having therein an exhaust-passage, a liquid-supply conduit and a conduit member communicating therewith and projecting longitudinally into said passage, a member supported by said conduit member and arranged to diffuse liquid therefrom into the path of exhaust fluids in said passage, and a valve supported by said diffusing member and arranged to permit flow of liquid from said conduits into said passage and to prevent flow of fluids in the opposite direction in said conduits. 105

9. A device of the kind described having therein an exhaust-passage, a valve susceptible of opening under the influence of fluid pressure within said passage and of closing under the influence of atmospheric pressure, a liquid-supply conduit and a conduit member communicating therewith and projecting longitudinally into said passage, a member supported by said conduit member and arranged to diffuse liquid therefrom into the path of exhaust fluids in said passage, and a valve supported by said diffusing member and arranged to permit flow of liquid from said conduits into said passage and to prevent flow of fluids in the opposite direction in said conduits. 115 120 125 130

10. A device of the kind described having therein an exhaust-passage, a liquid-supply conduit and a conduit member communicating therewith and projecting longitudinally into said passage, a member supported by said conduit member and arranged to diffuse liquid therefrom into the path of exhaust fluids in said passage, and a valve having a stem projecting into said diffusing member and arranged to permit flow of liquid from said conduits into said passage and to prevent flow of fluids in the opposite direction in said conduits.
11. A device of the kind described having therein an exhaust-passage, a valve susceptible of opening under the influence of fluid pressure within said passage and of closing under the influence of atmospheric pressure, a liquid-supply conduit and a conduit member communicating therewith and projecting longitudinally into said passage, a member supported by said conduit member and arranged to diffuse liquid therefrom into the path of exhaust fluids in said passage, and a valve having a stem projecting into said diffusing member and arranged to permit flow of liquid from said conduits into said passage and to prevent flow of fluids in the opposite direction in said conduits.
12. A device of the kind described comprising an outer casing, an inner casing constituting an exhaust-passage, there being a cooling-space between said casings having a liquid-supply inlet thereto, a transverse conduit opening to said cooling-space at opposite places in said inner casing, a conduit extending therefrom longitudinally into said passage, and a valve arranged to permit flow of liquid from said conduits into said passage and to prevent flow of fluids in the opposite direction.
13. A device of the kind described comprising an outer casing, an inner casing constituting an exhaust-passage, there being a cooling-space between said casings having a liquid-supply inlet thereto, a transverse conduit opening to said cooling-space at opposite places in said inner casing, a conduit extending therefrom longitudinally into said passage, and a valve arranged to permit flow of liquid from said conduits into said passage and to prevent flow of fluids in the opposite direction.
14. A device of the kind described comprising an outer casing, an inner casing constituting an exhaust-passage, there being a cooling-space between said casings having a liquid-supply inlet thereto, a valve susceptible of opening under the influence of fluid pressure within said passage and of closing under the influence of atmospheric pressure, a transverse conduit opening to said cooling-space at opposite places in said inner casing, a conduit extending therefrom longitudinally of said passage, and a valve arranged to permit flow of liquid from said conduits into said passage and to prevent flow of fluids in the opposite direction.
15. A device of the kind described comprising an outer casing, an inner casing constituting an exhaust-passage, there being a cooling-space between said casings having a liquid-supply inlet thereto, a valve susceptible of opening under the influence of fluid pressure within said passage and of closing under the influence of atmospheric pressure, a liquid-supply conduit leading from said

cooling-space into said passage, and a valve arranged to permit flow of liquid from said conduit into said passage and to prevent flow of fluids in the opposite direction.

16. A device of the kind described comprising an outer casing, an inner casing constituting an exhaust-passage, there being a cooling-space between said casings having a liquid-supply inlet thereto, a transverse conduit opening to said cooling-space at opposite places in said inner casing, a conduit extending therefrom longitudinally into said passage, and a valve arranged to permit flow of liquid from said conduits into said passage and to prevent flow of fluids in the opposite direction.

17. A device of the kind described comprising an outer casing, an inner casing constituting an exhaust-passage, there being a cooling-space between said casings having a liquid-supply inlet thereto, a valve susceptible of opening under the influence of fluid pressure within said passage and of closing under the influence of atmospheric pressure, a transverse conduit opening to said cooling-space at opposite places in said inner casing, a conduit extending therefrom longitudinally of said passage, and a valve arranged to permit flow of liquid from said conduits into said passage and to prevent flow of fluids in the opposite direction.

In testimony whereof I affix my signature in presence of two witnesses.

JOSEPH MARION KING.
